E. C. ALLEN

SIGNAL APPARATUS

Filed May 19, 1923

FIG. 1

FIG. 2

FIG. 4

Inventor
Edgar C. Allen
By Chundall Parker Carlson
Atty's

UNITED STATES PATENT OFFICE.

EDGAR C. ALLEN, OF ROCKFORD, ILLINOIS, ASSIGNOR OF ONE-HALF TO ROGER L. KNUTSSON, OF ROCKFORD, ILLINOIS.

SIGNAL APPARATUS.

Application filed May 19, 1923. Serial No. 640,008.

To all whom it may concern:

Be it known that I, EDGAR C. ALLEN, a citizen of the United States, residing at Rockford, in the county of Winnebago and State of Illinois, have invented a certain new and useful Signal Apparatus, of which the following is a specification.

This invention relates to signal apparatus for automobiles and motor trucks. The signal lamp or other electrical device of such an apparatus has heretofore been controlled by means of a knife switch or other form of mechanical switch supported at some point on the chassis and arranged to be operated through a link or the like connected to the brake pedal. Stop lights have heretofore proved very unreliable, as the switch and its operating connection were liable to be rendered inoperative by mud, by a stone bounding up from the highway or by other accidental causes.

The object of the present invention is to provide, in apparatus of this character, a form of switch which shall not be susceptible to injury by dirt, which shall be effectively protected against mechanical injury, and the operation of which shall be directly dependent upon actuation of the brake pedal, thus dispensing with intermediate operating connections.

In the accompanying drawings Figure 1 is a view in the nature of a diagram illustrating a stop light apparatus embodying the features of my invention. Fig. 2 is a sectional view taken in the plane of line 2-2 of Fig. 1. Fig. 3 illustrates the operation of the switch. Fig. 4 is a fragmental view illustrating an alternative arrangement.

In the drawings, 1 denotes a brake pedal of the ordinary or any suitable construction, arranged to be swung forwardly (i. e. in the direction in which the car normally travels) to decelerate the car, by pressure applied to the upper end 1^a of the pedal; 2 indicates a signal lamp casing of any preferred form located at any desired point upon the car, and 3 represents a battery of any ordinary or preferred character. The switch 4 for closing a circuit through a lamp in the casing 2 is shown in Fig. 3, and consists of a closed glass tube 5 within one end of which are the two contacts 6. The tube 5 contains a suitable quantity of mercury 7. In order to protect the switch 4 against injury, it is enclosed within a casing 8, which

may be a block of bakelite or similar material or a housing of any suitable construction.

In Fig. 1, I have shown the switch as secured to the brake pedal 1 below the upper end 1^a thereof by means of a clamp 9 (Fig. 2) comprising a set screw 10 and a lock nut 11, said screw being adapted to secure the clamp rigidly to the brake pedal. The switch is secured to the clamp by means of a screw 12 or the like extending through the casing 8 for the switch. When the brake pedal is in the normal position, as shown in Fig. 1, the globule of mercury is in the rear end of the tube and opposite to that containing the contacts 6, as shown in the upper portion of Fig. 3. When the pedal is depressed, the mercury flows to the forward end of the casing, thus closing a circuit through the signal lamp, as shown in the lower portion of Fig. 3. The flow of the mercury to the forward end of the casing is caused partly by the depression of the brake pedal, as indicated in Fig. 3, and partly by the momentum of the mercury as the car slows down, the momentum of the mercury serving to prevent rebounding of the globule.

In certain makes of motor cars there is rigidly attached to the brake pedal 1 a rearwardly extending arm 13 which is virtually a part of the brake pedal and to which the brake-operating link 14 is pivoted by means of a screw or stud passing through one of a plurality of holes 15 in said arm. Instead of mounting the switch directly upon the brake pedal 1, it may be conveniently attached to the arm 13 of said brake pedal by means of a bolt 16 or the like extending through the casing 8 and through one of the openings 15 in the arm 13, as shown in Fig. 4.

The construction herein shown is free from the objections and disadvantages inherent in previous constructions, inasmuch as the switch is thoroughly protected from the elements and from mechanical injury. Being attached directly to the brake pedal or the arm 13 rigid with said pedal, its operation is positive and reliable.

It will be understood that, while I have shown only two contacts in the tube 5, the number and arrangement of the contacts will depend upon the specific character of the signal device.

I claim as my invention:

1. In a motor car, the combination of a
brake pedal pivoted to swing forward to
decelerate the car, a signal device, a source
5 of electrical energy, and a mercury switch
for making and breaking a circuit through
said signal device and said source of energy,
said switch comprising a casing rigidly se-
cured to said pedal below the upper end
10 thereof, contact points within the forward
end of said casing, and a globule of mercury
within the casing to bridge said contact
points when said globule moves to the for-
ward end of the casing through the com-
15 bined action of momentum and the forward
swing of the brake pedal.
2. In a motor car, the combination of a
brake pedal pivoted to swing forward to de-
celerate the car, a signal device, a source of
20 electrical energy, and a mercury switch for
making and breaking a circuit thru said
signal device and said source of energy, said
switch comprising a casing mounted upon
said pedal to swing therewith, contact points
25 within the forward end of said casing, and
a globule of mercury within the casing to
bridge said contact points when said globule
moves to the forward end of the casing thru
the combined action of momentum and the
30 forward swing of the brake pedal.
3. In a motor car, the combination of a
brake member pivoted to swing forward to
decelerate the car, a signal device, a source of
35 electrical energy, and a mercury switch for
making and breaking a circuit thru said
signal device and said source of energy, said
switch comprising a casing secured to said
brake member, contact points within said
40 casing, and a globule of mercury within the
casing to bridge said contact points when
said globule moves in the casing thru the
combined action of momentum and the for-
ward swing of the brake member.

In testimony whereof, I have hereunto
affixed my signature.

EDGAR C. ALLEN.
